UNITED STATES PATENT OFFICE.

JULIUS PEGEL, OF PHILADELPHIA, PENNSYLVANIA.

DESIGN FOR A RUG.

SPECIFICATION forming part of Design No. 19,495, dated December 17, 1889.

Application filed November 23, 1889. Serial No. 331,378. Term of patent 3½ years.

To all whom it may concern:

Be it known that I, JULIUS PEGEL, a citizen of the United States, and a resident of Philadelphia, Pennsylvania, have invented a

5 Design for Rugs, of which the following is a description, reference being had to the accompanying illustration, making part hereof.

A is the middle panel, oblong and rectangular at its lower corners and having a curved 10 arched top B above.

C is the border. Conforming with the inner edge of the arch B is a line of leaves and scallop-work D, and within this arch diverging sprays E.

15 F F are flowers on the groundwork of the square part of the panel.

G is a fanciful ornamental figure in the

lower part thereof. Upon the groundwork between the panel and border are fanciful figures H H, approximating in appearance 20 vases of flowers.

I is an upper middle piece surrounded by smaller rounded scalloped figures J.

K is a pointed and curved line of fret-work around the lower part of the panel, with inner 25 ornamentation L L.

What I claim as new is—

A design for rugs, as shown.

In witness that the above is my invention I have hereunto set my hand.

JULIUS PEGEL.

Witnesses:

GEORGE E. BUCKLEY,
W. C. HOWARD.
